CLAIM

The ornamental design for a shock absorbing hub assembly for a marine propulsion apparatus, as shown and described.

DESCRIPTION

FIG. 1 is a front perspective view of a shock absorbing hub assembly for a marine propulsion apparatus, showing the new design, showing the body portion separated from the assembly for ease of illustration;

FIG. 2 is a top view thereof;

FIG. 3 is a bottom view thereof;

FIG. 4 is an end view thereof;

FIG. 5 is an opposite end view thereof;

FIG. 6 is a front perspective view of a hub component for the shock absorbing hub assembly, showing the body portion separated from the assembly for ease of illustration;

FIG. 7 is a top view thereof;

FIG. 8 is a bottom view thereof;

FIG. 9 is an end view thereof;

FIG. 10 is an opposite end view thereof;

FIG. 11 is a front perspective view of the shock absorbing hub assembly showing the new design, with the body and the elastic hub component assembled;

FIG. 12 is a top view thereof;

FIG. 13 is a bottom view thereof;

FIG. 14 is an end view thereof; and,

FIG. 15 is an opposite end view thereof.

The broken lines represent portions of the shock absorbing hub assembly for a marine propulsion apparatus that form no part of the claimed design.
